UNITED STATES PATENT OFFICE.

PHILIP BURNS, OF NORWICH, CONNECTICUT.

DESIGN FOR A CHAIN-LINK.

SPECIFICATION forming part of Design No. 25,914, dated August 11, 1896.

Application filed July 13, 1896. Serial No. 699,056. Term of patent 7 years.

To all whom it may concern:

Be it known that I, PHILIP BURNS, a citizen of the United States, residing at Norwich, New London county, State of Connecticut, 5 have invented and produced a new and original Design for Links for Drive-Chains, of which the following is a specification, reference being had to the accompanying drawings, illustrating my said design.

10 My said design consists of an elongated figure whose opposing sides are formed with inward curves *a*, extending approximately one-half the length of said figure, and of continued straight portions *b*, that approach each 15 other and finally terminate in a connecting semicircular line *c*, that outlines one end of the complete figure. At the opposite end of said figure the said curves *a* are connected by

an outwardly-curved semicircular line *d*, and within the field of the design is an opening *e*, 20 that is concentric with the said last-described curved end. Within said field, midway opposing points where the curves *a* and straight portions *b* meet, is an opening *g*, whose walls form, approximately, three-fourths of a circle, and leading therefrom toward the curved end *c* is an opening *h*, whose opposing side walls are parallel and whose end forms a semi-circle. 25

What I claim is—

30 The design for a link for drive-chains, substantially as herein set forth.

PHILIP BURNS.
